UNITED STATES PATENT OFFICE.

ERASTUS E. PIERCE, OF NEW BRIGHTON, PENNSYLVANIA.

MACHINE FOR FORGING HORSESHOE-NAILS.

SPECIFICATION forming part of Letters Patent No. 363,418, dated May 24, 1887.

Application filed June 3, 1886. Serial No. 204,069. (No model.)

To all whom it may concern:

Be it known that I, ERASTUS E. PIERCE, of New Brighton, in the county of Beaver and State of Pennsylvania, have made certain new and useful Improvements in Machines for Manufacturing Horseshoe-Nails, of which the following is a specification.

My invention relates to improvements in machines designed for use in the manufacture of horseshoe-nails by that particular method known to the art as "forging," and has for its object the provision of a machine of the class named wherein the end of a nail-rod is by gradual reduction quickly transformed into a nail-blank adapted to be subsequently finished by a separate machine.

To this end the invention consists in a series of roller-dies journaled to a suitable carrier and adapted to be successively brought into contact with the rod in manner very similar to that shown and described in Letters Patent No. 241,562, issued to me May 17, 1881, and upon which patent the present application is an improvement.

The invention further consists in the peculiar construction, arrangement, and operation of the several elements comprised in the machine, substantially as will be hereinafter fully described.

Referring to the accompanying drawings, which illustrate one embodiment of my invention, and wherein similar letters of reference denote similar parts, Figure 1 represents a side elevation, partly in section, of a horse-shoe-nail machine constructed in accordance with my invention. Fig. 2 represents a plan view of the operative parts of the machine. Fig. 3 is a sectional view of the die-carrier, taken on the line 1 2 of Fig. 1. Fig. 4 is a detail plan view of the rod-guide detached from the machine. Fig. 5 represents an elevation of a finished horseshoe-nail, showing one of the forms imparted by my invention. Fig. 6 is a plan of a pair of dies that operate to form the

sides of the nails and a center piece (or guide) in position slightly in advance of and between them. Fig. 7 is a detail sectional view taken on the line 45 46 of Fig. 1. Fig. 8 represents an elevation (with disk G and die G² removed) of dies G³, H', and K' acting on a nail-blank.

In carrying out my invention I employ a bed-plate, A, which, if desired, may be mounted

upon legs or supports. (Not shown herein.) I provide the bed A at one side of its middle with an aperture, a, and at its opposite side edges 55 with upwardly-projecting standards A', having at their upper ends journal-bearings that receive and support the rotatable driving-shaft B.

C designates the die-carrier, which is mounted upon the shaft B intermediate of the standards A' and rotates in unison with said shaft.

D D' designate gear-wheels, which are mounted upon the shaft B at each side of the carrier C and provided with sleeved hubs D² D³, that extend and are secured to the standards A' for the purpose of holding said wheels from rotation. One of said wheels—to wit, D—operates within a recess formed in one of the side faces of the carrier, and is provided upon its opposite sides with bevel gear-teeth 60 d d', that engage similar teeth formed upon bevel gear-pinions E E', mounted upon the inner ends of shafts F F', that are journaled in bearings formed radially through an annular flange, C', formed upon one side of the carrier C.

G G' designate disks which are mounted upon the outer ends of the shafts F F' and provided upon their outer faces with short studs g g. Dies G² G³ are mounted upon the faces 80 of the disks G G' upon prolongations of the shafts F F', or on screws f, that extend into said shafts and secure the dies thereto. Each stud g bears on a shoulder, g', of its die and insures the positive turning of the die with 85 the disk or shaft, and holds the die positively in position, yet the die may be quickly removed and replaced in exact position, the removal being effected by withdrawing the screw f.

H designates a peripheral groove formed about the carrier C intermediate of the shafts F F', within which are secured, by screws h, blocks H', the outer surfaces of which, at the rear ends thereof, are a little above (that is to 90 say, farther from the center of the roll-carrier) the outer surfaces of the disks G G', while said surfaces at the forward ends are inclined downward, as shown in Figs. 1 and 6. The blocks H' are placed slightly in advance of the disks, 100 and are provided at their rear ends with curved side faces. (See Fig. 6.)

By reference to the drawings, Fig. 1, it will be observed that the disks G G', having dies

G² G³, as above described, are arranged between the points 1 and 9 at equal distances apart upon the carrier, and the said dies are so formed and arranged as to gradually reduce 5 the nail-rod in lateral direction to the proper size and shape required.

I designates disks, similar in form and size with the disks G, that are mounted upon one end of shafts I', which turn in sleeves I², that 10 project through the carrier C outside of the flange C'. I provide the opposite ends of the shafts I' with gear-pinions I³, that engage and are rotated by the spur gear-wheel D'.

K designates dies which are mounted upon 15 the faces of each alternate disk I upon the projecting ends of the shafts I', or upon screws that extend into said shafts, and are caused to turn with said shafts by studs i, that project from said disks I in same manner as studs g g 20 on the disks G G'.

The dies K have smooth outer edges that impinge against one of the faces of the nail, and said edges have such size and configuration as, in conjunction with rollers L, to be 25 described, to gradually reduce the end of the nail-rod to the proper thickness and shape to form the desired nail-blank.

The said alternate disks I and their dies K are placed above small smooth-faced rollers L, 30 which turn loosely upon pins l, (shown by dotted lines,) that project from blocks l', that are held in position within corresponding recesses in the carrier by screws l², as shown by dotted lines at X, or by clips, as shown at Y, 35 Fig. 1. The rollers L operate within the groove H, as shown. The inner ends of the pins l enter recesses formed in the carrier at the opposite side of the groove H, as shown in Fig. 7. By this construction the rollers can be readily re- 40 moved and replaced in case of wear or injury. It will also be observed that the other alternate disks are mounted with guides K', similar in peripheral form to the dies K, but thin enough to operate between the dies G² G³, as 45 shown in Fig. 3. Each guide K' is placed immediately over one of the blocks H', slightly in advance of the centers of the disks G G', and operates, in conjunction with its block H', to prevent twisting or turning of the nail-blank 50 on its edge while being acted on by the dies G² G³. The different parts are maintained in the same relative positions to each other by being secured to and carried by the carrier C, and the hold of the blocks H' and guides K' 55 on the blank is always a little in advance of the point of contact of the dies G² G³ as they travel along the nail-blank, as shown by the drawings, Fig. 8.

Nails such as are represented by Fig. 5 are 60 not commonly used in the United States; but when it is desired to make such nails the beveling and bending dies P P' are used. The die P has a curved surface and a projection, and the die P' has two projections.

65 The operation of the dies P P' is as follows: The projection on the die P and the first projection on the die P' are simultaneously brought

in contact with the head of the nail-blank at its junction with the rod, and together act to bevel the top of the head, as shown in Fig. 5. 70 Immediately after this operation the second projection on the die P' comes in contact with the blank at the junction of the head with the shank to force it down against the curved surface of the die P and bend it so that the shank 75 is brought centrally in line with the head, as represented in Fig. 5. The nail-rod, instead of being held above the carrier, as in the machine described in the aforesaid patent, is supported below the carrier at an angle, with its 80 face projecting into the line of action of the dies, as in the said patented machine, and as shown in Fig. 1 and in dotted lines, Fig. 2.

Having described the means by which the nail-rod is reduced to the proper size and 85 shape of a nail-blank, I will now proceed to describe the means whereby the nail-blank is cut to the proper length and severed from the nail-rod. I accomplish the first of these objects—to wit, cutting the nail-blank to a pre- 90 determined length—by cutters N N', one of which, N, is secured by a screw, n, within a slot, n', formed in a block, N², secured to the face of a disk, N³, mounted upon one end of a shaft, N⁴, (shown by dotted lines, Fig. 1,) 95 that is journaled in the carrier C. This shaft is provided upon its opposite end with a gear-pinion similar to the pinions I³, that engages with and is rotated by the spur gear-wheel D'. The other cutter, N', is secured by a disk, N⁵, and nut n² upon the face of a disk, N⁶, that is mounted within a recess in the carrier upon the end of a shaft, N⁷, which turns in the carrier C, parallel with the shaft N⁴, and is operated in unison with the latter shaft through 100 engaging gear-wheels. (Shown by dotted lines, Fig. 1.) The cutters N N' are adapted to shear off any surplus metal at the point of the nail-blank, as will be understood. The nail-blank, after being brought to the required form and 105 size, is severed from the rod by adjustable cutters R R', the first of which is held by a screw, r, within a slot, r', formed in a cutter-head, R², secured to the face of a disk, R³, mounted upon a shaft turning in the carrier and operated in manner similar to shaft N⁴. The op- 110 posite cutter, R', is held within the face of a cutter-head, R⁴, which is secured by a screw, r², to the face of a disk, R⁵, mounted upon a rotatable shaft within a recess, r³, in the carrier. 115

The cutter R has a V shaped edge, which projects beyond or outside of the pitch-line of the driving-gear of the head carrying the cutter, while the cutter R' has a square or nearly square edge, which, as shown, is set at or a 120 little inside of the pitch-line of its driving-gear. While the carrier C moves in the direction of its arrow, Fig. 1, each cutter-head is revolved in the direction of its arrow, so that the shearing portions of the cutters do 125 not, for the time being, travel forward with the carrier, but move on lines approximately at right angles with the faces of the nail-rod.

If the cutters R R' were both of the same

shape and of equal length from the centers of the shafts, the head of the nail would be cut upon curved lines, forming a rib in the center; but by arranging the cutters as shown, one 5 projecting beyond and the other within the pitch-line of the gears, the line of movement of the shearing-edge of the cutter R is nearly at right angles to the faces of the nail-rod, and the latter is cut upon this line, forming 10 the face or end of the head at right angles to the line of the shank, as shown in Fig. 5.

The head R², having the cutter R, is beveled at r^4 , so that when the nail is severed from the rod it is forced downward by the square end 15 of the cutter R' and periphery of its head upon the bevel r^4 , and thereby quickly projected laterally from the machine and through the aperture a in the bed A to a suitable receptacle below.

20 S, Figs. 3 and 4, designates a guide-bar, which is adjustably held by a clamping-jaw, s, and screws s' to a bracket, S', secured to the bed A. The end s² of the bar S projects upward and is beveled, as shown in Fig. 4, to serve as 25 a bearing for and to guide the nail-rod T to the dies. A furnace, V, is secured to the bed A and operates as a support and guide to direct the rod to the guide S, which rod constitutes the support for the blank.

30 W W' designate feed-rollers, by which the rod is fed forward to and through the furnace. The several die-shafts, F, F', and I', and rolls L, and all other revolving parts in the carrier C, are supplied with oil in the following manner: To supply the shafts F F', I form a groove, C², in the inner surface of the flange C, which groove I connect by vents c⁵ with the journal-bearings of the shafts F F'. I supply oil to the groove C² through bores d⁷ d⁸, that extend 35 within the body of the gear-wheel D, from an annular groove, D⁴, formed in the sleeve D² of said gear-wheel. d⁶ designates an aperture opening into the groove D⁴. The shafts I' are provided with oil through bores c⁶, that extend 40 in the body of the carrier from the journals of the shafts I' to an annular groove, C⁷, formed in the face of the carrier, to which oil is fed through a funnel or tube, c⁸, that extends through the fixed wheel D' to said 45 groove. As will be readily understood, oil in the grooves C² and c⁵ will by centrifugal force be fed to the vents c⁵ and c⁶, and thence to the shafts F, F', and I', and all other bearings in the carrier C.

50 The oil for the rolls L passes from the groove C² to and through the pins l to the bearings of the rolls L on said pins l.

The nail-rod is first acted on by the die K and roll L, (the carrier rotating in the direction of the arrow o,) and is by said dies slightly elongated and reduced in thickness. The blank is next operated upon by the side dies, which reduce in width, elongate, and bend it into a plane parallel with the face of the carrier. It 60 is then operated on in consecutive order by each pair of face and side dies, and finally by the bending and beveling dies and cutters.

All the dies and rolls have plain ungrooved faces, and are relatively formed to draw down the head and shank of the blank to proper 70 shape.

I have herein shown and described the nail-rod as operated upon by the dies at the bottom of the carrier. This is of great importance, as thereby I am enabled to avoid all danger of the nails becoming entangled in the dies, as sometimes results when said nails are formed at the top of the machine. Although I have shown a certain number of dies, it will be understood that a greater or less number may be 75 employed if found desirable.

Without limiting myself to the exact construction shown, I claim—

1. The combination, in a horseshoe-nail-forging machine, of a rotatable die-carrier, rotatable dies upon said carrier arranged to simultaneously engage the opposite faces of a nail-blank, and a support, substantially as described, below the carrier-shaft to support and present such nail-blank to said dies below the 85 shaft of said carrier, as and for the purposes set forth.

2. A rotatable die-carrier provided with dies arranged in successive sets to operate simultaneously upon the opposite faces of a nail-blank, in combination with a furnace secured in a fixed position and constituting a guide for said blank, and feed-rollers to move the nail-bar forward through said furnace, substantially as described.

3. In combination, a supporting-bed, a rotatable die-carrier mounted thereon and provided with a series of dies to successively engage the opposite sides of a nail-rod, and a series of dies to successively engage the opposite faces of said rod, a furnace secured to said supporting-bed, and means, substantially as described, to feed the nail-rod through said furnace to said dies, as and for the purpose specified.

4. In a horseshoe-nail-forging machine, a rotatable die-carrier, in combination with a series of rotatable dies mounted upon said carrier, and means, substantially as described, for positively rotating said dies and for presenting a nail-rod between two series of dies supported by the carrier below the axis thereof, as and for the purpose specified.

5. In a nail-forging machine, a supporting-bed, a rotatable die-carrier mounted thereon and provided with a series of rotatable dies having gear-pinions, in combination with fixed spur gear-wheels for rotating said dies, and means, substantially as described, whereby the nail-rod is fed to said dies between the carrier 120 and its supporting bed.

6. In a nail-forging machine, a grooved die-carrier, a series of rotatable side dies, as G² G³, thereon, in combination with a series of blocks, H', substantially as described.

7. A rotatable die-carrier, side dies, G² G³, rotatably mounted thereon, in combination with blocks H' and rotatable face-guides K', substantially as described.

8. A grooved rotatable die-carrier, C, dies L, rotatably mounted thereon, in combination with blocks l', having journal - pins l, and means, substantially as described, for holding said blocks in position, as and for the purpose set forth. 45
9. The combination, with the carrier and its rotative dies, of the rollers L and pins supporting the rollers and supported each by a block secured detachably to the carrier, substantially as described. 50
10. The recessed carrier having detachable blocks l, fitting the recesses, and rollers carried by pins supported by said blocks, substantially as described. 55
11. The combination, with the dies having shoulders, of rotative disks having studs arranged to bear on said shoulders and securing devices connecting the dies detachably to the disks, substantially as described. 60
12. The combination, with the carrier, of a series of rotative side dies and a block arranged in advance of each pair of side dies, substantially as described. 65
13. The combination, with the carrier, of rotative side dies, blocks H' in advance of said dies, and face-guides, each revolving above one of said blocks, substantially as described. 70
14. In combination, a rotating carrier, side dies pivoted to said carrier, blocks, and face-guides, arranged substantially as described, said dies, blocks, and face-guides having plain ungrooved faces adapted to simultaneously operate upon all sides or faces of a nail-blank, substantially as and for the purpose set forth. 75
15. The combination of the carrier having side dies, blocks, and face-guides, arranged as described, and the face-dies and rolls arranged to operate upon a nail-blank in the same vertical plane, substantially as described. 80
16. The combination of the cutter shafts and heads, having cutters fixed thereto to sever a finished nail from a nail-rod, one cutter projecting beyond and the other at or within the pitch-line of the shaft-connecting gears, substantially as and for the purpose set forth. 85
17. The combination of the carrier, revolving cutter-heads and cutters, the outer head having a beveled edge and the inner head having a cutter arranged to force the blank against the said beveled edge, substantially as described. 90
18. The combination, with the rotating carrier and guides for presenting a nail-rod at an angle thereto, of rotating dies constructed and arranged, substantially as described, to bevel the head and bend the shank central with the head after the head is formed, substantially as set forth. 95
19. A rotatable die-carrier having a series of rotatable die-carrying shafts mounted therein, dies carried by said shafts, and annular and radial chambers to supply said shafts with oil, substantially as described. 100
20. A rotatable die-carrier, C, having rotatable dies and oil-receiving grooves C' c', in combination with fixed gear-wheels D D', having vents to conduct oil to said grooves, substantially as described. 105
21. A rotatable die-carrier provided with rotatable nail-forming dies, in combination with a guide-bar, S, arranged substantially as described. 110

In testimony whereof I have signed my name to this specification in the presence of two subscribing witnesses. 115
